Primary Examiner — Jack Reickel*Assistant Examiner* — Sydney M Evans(74) *Attorney, Agent, or Firm* — Keisling & Pieper PLC;
David B. Pieper; Trent C. Keisling(57) **CLAIM**

The ornamental design for a wire mesh pick support tree topper, as shown and described.

DESCRIPTION

FIG. 1 is a perspective view of a wire mesh pick support tree topper showing my new design;

FIG. 2 is a front view thereof;

FIG. 3 is a rear view thereof;

FIG. 4 is a left side view thereof, the right side being a mirror image thereof;

FIG. 5 is a top thereof; and,

FIG. 6 is a bottom view thereof.
